UNITED STATES PATENT OFFICE.

ABRAHAM BRAHADI, OF MONTREAL, QUEBEC, CANADA.

DESIGN FOR HEAD-WEAR.

SPECIFICATION forming part of Design No. 17,232, dated April 5, 1887.

Application filed March 3, 1887. Serial No. 229,642. Term of patent 7 years. Patented in Canada October 2, 1886, No. 702.

To all whom it may concern:

Be it known that I, ABRAHAM BRAHADI, a subject of the Queen of Great Britain, and a resident of Montreal, in the Province of Quebec and Dominion of Canada, have invented and produced a new and original Design for Head-Wear, of which the following is a specification, reference being made to the accompanying drawing, which represents a side elevation.

A represents the crown of a cap, which has a flat or nearly flat top, *a*, a curved and rearwardly-inclined back portion, *b*, and an inwardly-curved front, *c*. The brim *B* entirely surrounds the crown and fits closely to it at the rear *d*—the narrowest part of said brim.

It is gradually widened toward the front, where its edge projects forward from the crown, and its front portion flares outwardly, as shown at *e*. 20

What I claim is—

A design for head-wear, the same consisting of a crown having a flat top, an inclined and curved rear portion, and an inwardly-curved front, and a brim surrounding the crown, said brim being gradually widened from the rear to the front, where it flares outwardly, as described and shown. 25

ABRAHAM BRAHADI.
